UNITED STATES PATENT OFFICE.

JOHN SCHEROTTO, OF WEST HOBOKEN, NEW JERSEY, ASSIGNEE TO AMERICAN LITHOGRAPHIC COMPANY, OF NEW YORK, N. Y., A CORPORATION OF NEW YORK.

DISPLAY DEVICE.

Application filed July 12, 1921. Serial No. 484,091.

To all whom it may concern:

Be it known that I, JOHN SCHEROTTO, a citizen of the United States, and a resident of West Hoboken, in the county of Hudson and State of New Jersey, have invented certain new and useful Improvements in Display Devices, of which the following is a specification.

This invention relates to display devices and particularly to that class thereof which is adapted to engage and be supported by a merchandise container. The object of my improvements is to provide a device of simple construction and one having efficient and reliable means for self-supporting engagement with the container to which it is applied.

With these ends in view my improvements comprise features illustrated in their preferred embodiment in the drawing accompanying this specification, wherein:

Figure 1 is a perspective elevation of my improved device erected in position. Fig. 2 is a fragmentary detail sectional elevation showing a modification of my improvements. Both figures are to the same scale.

My improved device is particularly applicable to that class of containers, usually made of sheet material, which is provided about its top with an opening within which is inserted a cover having an upstanding flange in engagement with the edge of said opening. One example of such class is the commonly known paint can such as illustrated in Fig. 1 of the drawing. My improved device is equally applicable to the common type of glass milk bottle, see Fig. 2, and to numerous other containers of various cross sectional contours, whether circular, oval or polygonal, so long as each is provided with an upstanding flange, as 2, Fig. 2, surrounding a cover supporting ledge 3, within and below the top of said flange. Also the efficient operation of my improved device and its applicability to the particular container on which it is mounted are quite independent of the presence or absence of a cover on such container.

Directing attention now to Fig. 1 of the drawing, my improved device comprises two leaf portions 4, 5, joined along two similar edges at 6. For simplicity of construction said two members are preferably made from one piece of cardboard or the like, folded along said line 6. Said members 4, 5 are

preferably similar in profile and the display portions as 7 of one or both may be of decorative outline. Those edges of said members 4, 5 opposite their line of articulation 6 are of peculiar contour and are adapted for engagement with the container on which the display device is mounted. Directing attention now particularly to member 4, member 5 being preferably a substantial duplicate thereof, said member 4 is provided with two downreaching opposite ears 9, 10 spaced apart a distance slightly less than the major transverse dimension of the container to which the device is to be applied. Also the inside edges 11, 12, respectively, of said ears are usually parallel but said edges may obviously vary from such relation, to conform to various body shapes of containers. Lying between said ears and a substantial distance above their lower edges 13, 14, respectively, is flange engaging wing 8 preferably having a profile conforming to the inside wall 15, Fig. 2, of the container flange. Said wing 8 is articulated at 16 to member 4 preferably normal to ears 9, 10 and when erected in position is bent outwardly from member 4 at approximately right angles so as to lie within the flange of cover 17, Fig. 1, or within the flange 2, Fig. 2.

On each side, between wing 8 and ears 9, 10, member 4 is provided with pockets 18, 19, respectively, adapted to span the container flange. While in Fig. 1 said pockets are illustrated as of rectangular profile it will be obvious that other profiles, to conform to other characters of flange profile, such as the curved profile of Fig. 2, may be employed when desired. While members 4, 5 may be identical in profile, including the wings, as 8, it will be understood that as far as the outward folding of said wings is concerned, said members are opposites, the wing of member 4 being folded forwardly and the wing of member 5 being folded backwardly.

The operation of my improved device will be obvious from the drawing and description. Suffice it to state that the device is pushed downwardly over the container top, with the ears 9, 10 of member 4 forward of the transverse axis of the container top and wing 8 is seated forwardly as shown; at the same time the ears of member 5 are pushed downwardly over the container top rearwardly of said transverse axis and its wing is seated rearwardly within the container

flange. This brings members 4, 5 into diverging relation at their lower ends while maintaining their articulated relation at their upper ends at 6. There is thus provided a rigid and substantial display structure.

I claim:

1. A display device adapted for erection on the top of an upstanding container including in combination two members of sheet material articulated along their upper edges, and two opposite ears downwardly reaching from each of said members spaced apart a distance slightly less than the major transverse dimension of the container.
2. A display device adapted for erection on the top of a container having an upstanding flange including in combination two members of sheet material articulated along their upper edges, two opposite ears downwardly reaching from each of said members, and a wing articulated to each of said members between said ears for peripherally engaging the inside of the container flange.
3. A display device adapted for erection on the top of a container having an upstanding flange including in combination two members of sheet material articulated along their upper edges, two opposite ears downwardly reaching from each of said members, the distance between said ears being less than the major transverse dimension of the container on which said device is adapted to be erected, and a wing articulated to each of said members between said ears for peripherally engaging the inside of the container flange.
4. A display device adapted for erection on the top of a container having an upstanding flange including in combination two similar members of sheet material articulated along their upper edges, two opposite ears downwardly reaching from each of said members having parallel inside edges, and a wing articulated to each of said members between said ears for peripherally engaging the inside of the container flange.
5. A display device for containers including in combination two members of sheet material articulated along their upper edges, two opposite ears downwardly reaching from each of said members, a wing articulated to each of said members between said ears, and a pocket between each end of said wing and its adjacent ear, said pockets

being adapted to span the flange of a container to which the device is applied.

6. A display device adapted for erection on the top of a container having an upstanding flange including in combination two similar members of sheet material articulated along their upper edges, two opposite ears downwardly reaching from each of said members having parallel inside edges, the distance between said ears being less than the major transverse dimension of the container on which said device is adapted to be erected, and a wing articulated to each of said members between said ears and normal thereto for peripherally engaging the inside of the container flange.

7. A display device for containers including in combination two similar members of sheet material articulated along their upper edges, two opposite ears downwardly reaching from each of said members, the distance between said ears being less than the major transverse dimension of the container on which said device is adapted to be erected, a wing articulated to each of said members between said ears and normal thereto, said wing being adapted to engage the inside of the flange of a container to which the device is applied, and a pocket between each end of said wing and its adjacent ear, said pockets being adapted to span a container flange.

8. A display device for containers including in combination two members of sheet material articulated along their upper edges, two opposite ears downwardly reaching from each of said members, the distance between said ears being less than the major transverse dimension of the container on which said device is adapted to be erected, a wing articulated to each of said members between said ears and normal thereto, and a pocket between each end of said wing and its adjacent ear, said pockets being adapted to span the flange of a container to which the device is applied.

9. A display device adapted for erection on the top of a container having an upstanding flange including in combination two members of sheet material articulated along their upper edges, and a wing articulated to the lower edge of each of said members for peripherally engaging the inside of the container flange.

In witness whereof, I hereby affix my signature this 7 day of July, 1921.

JOHN SCHEROTTO.
